UNITED STATES PATENT OFFICE.

JOHN NICHOLAS SCHMITZ, OF CLINTON, IOWA.

HORSE-COLLAR.

SPECIFICATION forming part of Letters Patent No. 769,026, dated August 30, 1904.

Application filed December 17, 1902. Serial No. 135,613. (No model.)

To all whom it may concern:

Be it known that I, JOHN NICHOLAS SCHMITZ, a citizen of the United States, residing at Clinton, in the county of Clinton and State of Iowa, 5 have invented a new and useful Horse-Collar, of which the following is a specification.

This invention relates to horse-collars.

The object of the invention is to provide a horse-collar which may be adjusted to fit the 10 neck of the animal to cause the same to be comfortable and easy in use, to obviate galling of the neck, to prevent splitting of the hames under strain, to provide efficient means for adjusting both the top and the bottom of 15 the collar, either one to the exclusion of the other, and, finally, to improve the general construction of devices of this character.

With these and other objects in view, as 20 will appear as the nature of the invention is better understood, the same consists in the 25 novel construction and combination of parts of a horse-collar, as will be hereinafter fully described and claimed.

In the accompanying drawings, forming a 25 part of this specification, and in which like characters of reference indicate corresponding parts, there is illustrated one form of embodiment of invention capable of carrying the same into practical operation, it being understood 30 that the elements therein exhibited may be varied or changed as to shape, proportion, and exact manner of assemblage without departing from the spirit thereof.

In the drawings, Figure 1 is a view in front 35 elevation of a horse-collar embodying the features of the present invention. Fig. 2 a view in vertical transverse section. Fig. 3 is a detail view of the lower portion of the collar. Fig. 4 is a perspective detail view of the 40 means for effecting adjustment of the lower ends of the collar. Fig. 5 is a transverse sectional view through one of the hames, showing the means by which the draft tug-bolt is held associated therewith and also a band or 45 strap for reinforcing the hames at the point of attachment of the draft-plate.

Referring to the drawings, 1 designates the hames, which may be constructed of any suitable material, preferably of wood, and in order 50 to prevent the same from splitting and to

reinforce them rivets or screws 2 are employed, which may be disposed at such points on the hames as will be best adapted for effecting the purpose designed. The fronts of the hames are padded at 3 in the usual or any preferred 55 manner to present a soft and thoroughly-comfortable structure.

The novelty of the present invention resides principally in the provision of means for adjusting the upper ends of the hames with 60 relation to each other, in the provision of a cap or yoke supported by and independently movable with relation to the hames, so as to rest upon the top of the horse's neck and to be adjustable to the different positions according to the movement of the hame-sections, and the provision of means for adjusting the lower ends of the hames, together with a shield for bridging the lower opposed 65 ends of the hames, thereby to prevent tendency of choking the animal.

The means for effecting the adjustment of the upper ends of the hames comprises a bar 4, provided near each terminal with a plurality of transverse grooves or depressions 75 5, adapted to be engaged by the bends of a pair of clips 6, which project through reinforcing-plates 7, suitably secured to the hames, the ends of the clips being threaded for the reception of nuts 8, by which the clips may 80 be securely clamped within one of the grooves 5. The grooves are to be of such depth that when the clips are seated therein, while the collar-sections will be permitted to have a range of movement on the bar, they will be 85 positively prevented from disconnection therewith. By permitting this rocking motion of the hame-members upon the adjusting-bar the collar as a whole will adjust itself automatically to the animal's shoulders, and 90 thus present a more comfortable device in wear.

The means for supporting the collar upon the neck of the animal and also for permitting the hame-sections to have the motion 95 above referred to comprises a cap or yoke 9, preferably made of leather and in two plies assembled by suitable means, as by rivets, the outer ply 10 having secured to it on each side a metallic reinforcing-plate 11, said plates 100

being connected with the ply by rivets 12. Passing through the outer ply and through the reinforcing-plates are bolts 13, which through the medium of nuts 14, screwed thereon, serve to clamp the reinforcing-plates against the under sides of the hames. The manner of connecting the adjusting-rod 4 and the cap 9 with the hames is such that the hames may be separated longitudinally, thus 5 to permit of their being placed over the animal's neck and obviating the objection of having the hames open laterally, as is common.

Means for adjustably connecting the lower 15 ends of the hames comprises a plate 15, carrying a swiveled link 16, and an L-bolt 17, having a rigid link 17^a. The plate is provided with a plurality of orifices 18 to be engaged by the outturned end 19 of the bolt, a nut 20, 20 screwed on the said end, serving to hold the hames at the desired adjustment. It will be seen that by shifting the bolt from one to the other of the openings 18 the hames members may be adjusted laterally to cause them to fit 25 animals of different sizes.

The link of the bolt 17 is held in operative position with relation to the hames by a plate 21, bolted to the hames, and the link 16 of the plate is designed to engage a hook 22 on a 30 plate 23, bolted to the other hame, a latch 24, pivoted to the last-named plate, being adapted when turned in under the hook 22 to prevent disconnection of the link therefrom. When the collar is to be removed, the latch 35 24 is swung upward, as shown in dotted lines in Fig. 3, whereupon the link will be free to move out of engagement with the hook 22. In order to avoid any choking of the animal or discomfort in use, there is a shield 25 provided, which, as shown in Fig. 2, is folded 40 around the plate and the bolt and is held in position by the nut 20, as clearly shown in Fig. 1. This shield presents a smooth rounded surface to bear against the animal's throat 45 and will add greatly to its comfort when drawing heavy loads.

As a means for reinforcing the hames and also to prevent disconnection of the draft-tug bolts 26 therefrom a reinforcing-band 27 is 50 employed, preferably of sheet metal, which

is secured to the front end of the hames before being padded, thence bent around the hames, and is held in place by having its end provided with an opening to pass over the outer end of the bolt 26. It will be seen that 55 when the nut 28 of the bolt 26 is loosened should it be desired to remove the draft-tugs 29 the said bolt will be prevented from slipping inward, and thus dropping into the stuffing of the hames and causing trouble and expense to replace it.

While all of the improvements of this invention are simple in character, they are of great utility and will be found thoroughly effective in accomplishing the results sought 65 and by reason of the simplicity of the parts may be readily applied to an ordinary collar without necessitating any marked change in the structural arrangement.

Having thus described the invention, what 70 I claim is—

1. The combination with two hame members each having spaced apertures extending transversely therethrough, of a transversely-disposed bar having a series of transverse terminal notches, and adjusting means on the respective hames comprising U-shaped clips having the legs thereof extended through the spaced apertures in said hame members and provided with screw-threaded terminals, the 80 bases of said clips being seated in the notches of said bar, and nuts engaging said screw-threaded clip ends to securely hold the clips in said notches and unite the parts.

2. The combination with two hame members, 85 of a transversely-disposed bar having transverse terminal notches, U-shaped clips loosely engaging said notches and extending through said hame members to provide for the free and independent movement of the hame members, and means connecting said clips with 90 said hame members.

In testimony that I claim the foregoing as my own I have hereto affixed my signature in the presence of two witnesses.

JOHN NICHOLAS SCHMITZ.
